UNITED STATES PATENT OFFICE.

WILLIAM G. HUGHES, OF PITTSBURGH, PENNSYLVANIA.

DENTAL-AMALGAM MIXER.

1,173,519.

Specification of Letters Patent. Patented Feb. 29, 1916.

Application filed May 18, 1915. Serial No. 28,901.

To all whom it may concern:

Be it known that I, WILLIAM G. HUGHES, a citizen of the United States, residing at Pittsburgh, in the county of Allegheny and State of Pennsylvania, have invented certain new and useful Improvements in Dental-Amalgam Mixers, of which the following is a specification.

This invention relates to certain new and useful improvements in dental amalgam mixers.

The primary object of this invention is to provide a device especially adapted for dental use for mixing amalgam for teeth fillings, and whereby a greater edge strength is produced with a slight saving of mercury, a complete control of the setting properties of the amalgam being also provided.

A further object is to provide a mixer operable by the usual dental engine and whereby the alloy and mercury are rapidly and accurately mixed to the proper filling consistency, the ingredients being rolled either toward a common center, or outwardly as desired.

A still further object of the invention is to provide a mixing tool revolved in either direction by insertion within the chuck of a dental engine and capable of mixing amalgam for silver fillings and capable of imparting different mixing movements to the ingredients by a grooved arrangement of the tool and the direction in which the same is actuated.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like-designating characters refer to corresponding parts throughout the several views, Figure 1 is a side elevation of the operative connections of a dental engine illustrated in use in connection with the present device, the cup or mortar thereof being shown in central vertical section. Fig. 2 is a top plan view of the mixing tool or pestle employed with the device, and Figs. 3 and 4 are partial radial sectional views taken upon lines III-III and IV-IV respectively of Fig. 2.

Referring more in detail to the drawings,

the device is best illustrated in Fig. 1 operatively positioned in connection with a hand piece 10 of a dental engine of the usual construction and having the usual wrist piece 11 and chuck adjustment 12.

A mortar or cup 13 is provided within which the ingredients are adapted to be mixed for forming the amalgam, the said cup being in the form of a cylindrical member preferably formed of metal and having a receiving chamber 14 milled out of its upper face 15 thereof, the said chamber having a substantially semi-spherical inner end or bottom 16.

The pestle or mixing tool consists of a spherical member or ball 17 preferably formed of metal and having a radially arranged shank or stem 18 projecting therefrom and adapted to be received and retained within the engine chuck in the outer end portion 19 of the hand piece 10.

The diameter of the ball 17 is such as to allow the ball to closely fit within the bottom 16 of the chamber 14 and to operatively engage the alloy which is placed in the cup and to mix the same with the mercury which is added thereto during the rotation of the ball by the dental engine.

The ball 17 is provided upon its face opposite the stem 18 with oppositely positioned communicating curved grooves 20 tapering toward their diametrically opposite free ends 21. The said grooves 20 are each substantially crescent-shaped and when taken together are substantially S-shaped, while the cutting of the grooves within the spherical body of the pestle 17 forms slightly sharpened inner curved edges 22 which assist in pulverizing and mixing the ingredients as the pestle revolves in a scouring movement within the receiving chamber bottom 16 which semi-spherically conforms to the shape of the pestle. The provision of the curved cutting edges is a distinctive feature of the improvement, said edges coacting with the smooth semi-spherical bottom of the mortar to insure a thorough pulverization and admixing of the ingredients used. During the operative rotation of the pestle ball 17 in a direction from left to right, the amalgam ingredients will be rolled from the outer circumference toward the center, while a reverse rotation of the ball will roll the ingredients outwardly and in this manner a complete and thorough mixing is accomplished. The proper con-

sistency for the silver filling is derived in the usual manner by regulating the amount of mercury added to the mortar, although less mercury is required in view of the added efficiency in mixing the same, the setting of the amalgam being controlled by regulating the speed of the mixing operation. The flaring sides of the chamber 14 allows the hand piece 10 and pestle shank 18 to be given desirable gyratory movements during the operative rotation of the ball pestle.

It will be understood that any operating means may be provided for imparting the necessary revolutions to the ball pestle as well as employing different forms of receiving mortar therefor without departing from the spirit and scope of the invention as claimed, while minor details of construction may be likewise changed.

What I claim as new is:—

1. A spherical head for rotary pestles having on its under mortar-engaging surface a plurality of arcuate grooves having their centers eccentric in plan to the vertical axis of the pestle and meeting centrally of the bottom plan of the head.
2. A spherical head for rotary pestles

Copies of this patent may be obtained for five cents each, by addressing the "Commissioner of Patents, Washington, D. C."

having on its under mortar-engaging surface a plurality of arcuate grooves having their centers eccentric in plan to the vertical axis of the pestle and meeting centrally of the bottom plan of the head, said grooves broadening from their outer extremities to their meeting plane.

3. The combination with a mortar having a material receiving recess of inverted frusto-conoidal form and having a hemispherical extension forming its bottom, and a grinding sphere having its lower hemisphere located in the hemispherical extension and provided with a mill dress.

4. The combination with a mortar having a material receiving recess of inverted frusto-conoidal form and having a hemispherical extension forming its bottom, and a grinding sphere having its lower hemisphere located in the hemispherical extension and provided with a mill dress, the outer portions of the mill dress terminating just below the upper part of the hemisphere and the center of the dress forming a gathering chamber.

In testimony whereof I affix my signature.

WILLIAM G. HUGHES.
